CONTAINER

Abraham H. Berwald, New York, N. Y., assignor
to Eagle Pencil Company, Inc., New York, N. Y.,
a corporation of Delaware

Application May 14, 1937, Serial No. 142,613

2 Claims. (Cl. 206—46)

Among the objects of the present invention are to provide a container having a grade or similar designation thereon, so arranged and displayed as to focus attention to said designation so that it will not be overlooked, and impliedly indicate from which end the container is to be properly opened and which will enhance the attractiveness of said container.

As a feature of the present invention the container comprises a casing and a member movable in or out of said casing and having a grade or other similar designation thereon visible through a cut-out or window in a wall of said casing when said container is closed.

As another feature the movable member above referred to is in the form of a closure flap which is adapted to be tucked underneath the wall having the cut-out or window.

As a further feature, this closure flap forms part of a container section, which is slideable in the casing and which carries therewith the contents of the container so that said contents is accessibly exposed by the sliding manipulation of said section into open position.

In the accompanying drawing in which are shown one or more of various possible embodiments of the several features of the invention—

Fig. 1 is a perspective of a closed container embodying the present invention;

Fig. 2 is a perspective of the container of Fig. 1 but shown in open position;

Fig. 3 is a section taken on line 3—3 of Fig. 1;

Fig. 4 is a plan view of the blank from which the casing is formed;

Fig. 5 is a plan view of a flat strip from which the slideable section of the container is formed, but shown in reduced scale; and

Fig. 6 is a perspective of a form of pencil lead for which the container of the present invention is particularly adapted.

Although the present invention is adapted for a large variety of uses, it is particularly useful for pencil lead containers, a specific form of which includes a tubular open ended casing 10 of rectangular cross-section, formed from a blank 11, which is made preferably of pasteboard, and which has a series of longitudinally extending score or crease lines 12 along which said blank is folded to form a pair of opposed side walls 13, a top wall 14, and a pair of overlapping sections preferably glued together to form a bottom wall 15. This bottom wall 15 is preferably provided at the ends with semi-circular cut-outs 16 and 17 to facilitate pushing and pulling manipulations of the container into open position as will be hereinafter made apparent.

Slidably extending in the interior of the casing 10 is a block 18 preferably of wood, having a series of longitudinally extending grooves 20 opened at their ends and at their upper sides, and 5 adapted to receive long pencil leads 21 of the type to be used in mechanical pencils. The length of the block 18 is substantially co-extensive with the length of the casing 10, and its cross section is slightly smaller than the cross section of the casing to permit the free sliding movement of said block in said casing.

The leads 21 are shown of the type described and claimed in the copending application Serial No. 52,969, of Isidor Chesler, filed December 5, 1935, in which a coating 22 of contrasting color is provided at one end to apprise the user of the need for recharging, when the colored end of the lead appears through the tip of the mechanical pencil.

Wrapped longitudinally around the block 18 is a band 24 forming a closure for the casing 10, and comprising a longitudinal strip preferably of pasteboard, provided with transverse score lines 23 defining a main panel 24a co-extensive in length and width with the length and width of the block 18 respectively, and adapted to extend along the bottom thereof, a pair of intermediate spaced panels 25 adapted to be folded upwardly across the ends of the block 18, and a 20 pair of end closure flap sections 26 and 27 adapted to be folded inwardly over the top of the block 18, and to be tucked under the top wall 14 of the casing 10. The outer ends of these flap sections 26 and 27 are preferably tapered to facilitate the 25 tucking of said sections into closure position.

As an important feature of the present invention the top wall 14 of the casing 10 is provided near one end with a cut-out 28 preferably of circular form, and the flap 26 has a grade legend 40 or designation 29 which in the present embodiment indicates the hardness of the lead. This designation 29 is so positioned on the flap 26 that when the container is closed in the position shown in Fig. 1, said designation will appear centrally 45 through the cut-out 28. One of the end panels 25 of the band 22 is preferably provided with a legend 30 indicating the color of the lead.

The band 24 on its outer side is of a color 50 which preferably corresponds to the color of the lead, and which contrasts with the colorings on the top wall 14 of the casing. For instance, the end portion of the top wall 14 of the casing may be in silver or white, the outer surface of the band may be in black, corresponding to the color 55 of the lead, and the legend 29 in white, so that

the black background of said legend will contrast with said casing top and will at the same time indicate the color of the lead. In opening the container the user pushes his finger through the right-hand end of the casing, so that the left-hand end of the block 18 and the band 24 will be projected a comparatively small distance beyond the left-hand end of said casing. This projecting end of the block 18 and band 24 may then be pulled until the flap 26 is released from the top wall 14 of the casing. When this flap 26 is so released it will spring outwardly as shown in Fig. 2 and will expose the coated ends of the lead. A lead may then be conveniently withdrawn from the block 18.

The prominence of the cut-out 28 will focus attention immediately on the grade mark 29, so that a purchaser will not overlook this mark among a general maze of printing on the carton, and will therefore not inadvertently accept the wrong grade of lead. Furthermore, the present construction permits the casings 10 to be manufactured all alike for different grades of leads, and effects a color contrast for the grade designation without the necessity of subjecting the casing itself to an additional color printing operation for this contrast. Also, since the cut-out 29 appears near the end of the casing adjacent to the coated ends of the leads, it will impliedly indicate that the container is to be opened from that end. When the purchaser therefore properly opens the casing, he will immediately see the colored ends of the leads and he will not therefore inadvertently insert the wrong end of a lead into the mechanical pencil.

It must be understood that as far as certain aspects of the invention are concerned, the closure flap bearing the grade or similar designation may be integral with the casing 10, or the closure flap may be eliminated and the block 18 itself contain the designation which appears through the cut-out or window of the casing 10. Also as far as certain aspects of the invention are concerned, the cut-out 28 may be covered with a transparent film such as "Cellophane" to form a window.

It will thus be seen that there is herein described a container in which the several features of this invention are embodied, and which container in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accom-

panying drawing shall be interpreted as illustrative and not in a limiting sense.

Having thus described my invention, what I claim as new and desire to secure by Letters Patent is:

1. A container including a tubular pasteboard casing of rectangular cross section open at both ends, and having a cut out in its top wall near one end thereof, a block in said casing having a length and cross section substantially coextensive with that of said casing, and provided on its upper side with a series of parallel lead retaining grooves open at the ends of said block, and a longitudinal pasteboard band provided with transverse score lines defining a main panel coextensive in length and substantially in width with the length and width of said block respectively, and extending along the bottom thereof, a pair of intermediate spaced panels adapted to be folded upwardly across the ends of the block, and coextensive in length and width with the height and width respectively of said block ends, and a pair of end closure flap sections adapted to be folded inwardly over the top of said block, and to be tucked under the top wall of said casing, one of said end sections having a designation thereon visible through said cut out when said container is in closed position, said latter section being held against said cut-out by said block.

2. A container including a tubular pasteboard casing of rectangular cross-section, open at both ends and having a cut-out near but spaced from one end of its top wall and having cut-outs at the ends of its bottom face, serving as finger notches, a block in said casing having a length and cross-section substantially coextensive with that of said casing and provided on its upper side with a series of parallel lead retaining grooves open at the ends of said block, and a longitudinal pasteboard band provided with transverse score lines defining a main panel coextensive in length and substantially in width with the length and width of said block respectively, and extending along the bottom thereof, a pair of intermediate spaced panels adapted to be folded upwardly across the ends of the block, and coextensive in length and width with the height and width respectively of said block ends, and a pair of end closure flap sections adapted to be folded inwardly over the top of said block, and to be tucked under the top wall of said casing, one of said end sections having a designation thereon visible through the cut-out in said top wall when said container is in closed position, said latter section being held against said cut-out by said block.

ABRAHAM H. BERWALD.
